UNITED STATES PATENT OFFICE

100,144

DESIGN FOR A BOAT

Herman E. Bakenhus, Azusa, Calif.

Application April 7, 1936, Serial No. 61,993

Term of patent 14 years

To all whom it may concern:

Be it known that I, Herman E. Bakenhus, a citizen of the United States, residing at Azusa, in the county of Los Angeles and State of California, have invented a new, original, and ornamental Design for a Boat, of which the following is a specification, reference being had to the accompanying drawing, forming part thereof.

I claim:—

The ornamental design for a boat as shown.

HERMAN E. BAKENHUS.
